Jeremiah S. Colman
Yellow Patent

The date referred to in the Yellow Patent is making part of the
same containing a description in the name of the said Jeremiah S. Colman
himself of his improvement called the self-regulating, Horizontal wind
mill.

Be it known that Jeremiah S. Colman of Winona of the County of
Berry and State of Indiana have invented a new and useful improvement
in the application of wind to machinery and that the following is a full and
exact description of the construction and operation of said machine as invented
by natural Gravity or Wind or J. S. Colman's self-regulating horizontal
wind mill, for working any kind of machinery which is propelled by applying
weight on beams. Figure 1 represents one of the wings or sails stand-
ing inclining to the left or backwards from dotted line A which shows a right
of the wing to the left. The inclination may be more or less than represented by
the wing and dotted line agreeable to the natural weight of the wing.

Not give it such inclination back from the way which the wind mill is
calculated to run as will give sufficient weight to wing say one light
one of millstones - of man power as desired and the same sufficiently strong
and have weight to the wings to give the wings more inclination which
may be effected by hand, stopping the mill and moving a piece of timber
on which the wings turn, or at D, where said timber moves on a smooth sur-
face turning on a pivot on the wind shaft, or the wings may be inclined more
a less without stopping the mill by the following described machinery, by
hanging a piece of timber with teeth, as represented at D, which moves up
down in a groove in the wind shaft and passes under a collar on
the wind shaft as at E, with moving joint at F and, when it is attach-
ed to a triangular frame of wood in view with a stationary pivot at H
a piece of timber running from E to H there is another moving joint to
K, where it joins on a triangular as the one above described, by a man
standing on a wheel or platform on wind shaft at L, and turning a small

G
J. S. Colman

small pinion wheel with a work at N. The tail arm with tail spar
and at D is made of a iron which moves the tail part of the arm
at D by the above described machinery by a leather band by which motion
will be given. Figure 2 is a view of a mill in operation in a high
place of wind. May 1st receiving the wind on its back side as it
comes from the west. May 2nd receiving the wind on its back the same
as above. May 3rd coming with its thin end to the wind. May 4th re-
ceiving the wind as it comes from the north passing on front of May 5th
and back of wing 1st which wing stands as a monolith and stands
in front of wing 2nd. Each wing performing oscillation on its front
to meet main wind wheel if the wind be sufficient. The above described
mill is safe with alreadly rigid wings, as each wing when a storm
stands with its thin edge to the wind. The wind having ~~the~~ little more
power if any than the great weight of the wings on the wind. On stopping
the mill friction levers may be lightly drawn across a part of the tail part
a cordage which will be sufficient to over balance the weight of the wings
above and the mill stops. All the bracing within the arm about at D
in Figure 2 may be dispense with on a small scale, leaving the center
post sufficiently large. The running gears may be as in any other mill
geared from a vertical shaft, to meet such machinery as is calculated
to be done. The machinery ought to have its proper space when the
wings are moving say 5 miles an hour - a little more or a little less will do.
The wings may be covered with light boards or canvas. Received March
31st 1832.
